METHOD OF STOKING FURNACES

Herman L. Kraeft, Cleveland, Ohio, assignor to
 Murray-Ohio Manufacturing Company, Cleve-
 land, Ohio, a corporation of Ohio

Application June 18, 1932, Serial No. 617,977

6 Claims. (Cl. 110—115)

This invention is concerned with methods of stoking furnaces and is directed particularly to overfeed stoking of domestic heating furnaces and has for an object the provision of a coal stoking method which will be readily adaptable to use with various types of domestic furnaces, and which will be efficiently active with the functionings of thermostatic controls and whereby efficient combustion will be obtained.

Various types of coal stokers have been proposed some of which have been manufactured heretofore for the purpose of feeding fuel to domestic heating furnaces. Such stokers have usually been of the underfeed type, while others have been of the overfeed type. The present invention is concerned with the overfeed method of stoking and overfeed type of stoker and has been developed to be readily adaptable to hot vapor, steam and hot air types of furnaces, regardless of the variation in design of the furnace housing and dimensional variations in the fire boxes of such furnaces.

Furthermore, the invention has been developed to meet widely varying conditions in the handling of different kinds of coal and regardless of the degree of dryness or dampness of such coal. The invention has been used in connection with a stoker mechanism, which may be brought into cooperative relation with a furnace structure without necessitating any serious alteration of the furnace structure at the time of installation, and the nature of the method is such that the fuel will be evenly spread upon the fire bed without causing excessive dust or uncombusted gases to escape up the furnace flue, all of which I accomplish while avoiding fire hazards.

My method of feeding the fuel while fulfilling the foregoing stated purposes is to agitate a substantially large supply of the fuel by revolving the fuel to cause the pile of fuel to settle downwardly, whereupon I remove relatively small amounts of the fuel from the settling pile by shifting such amounts in a substantially horizontal direction toward the fire bed, and while shifting the fuel I permit it to escape intermittently over a ledge in substantially measured quantities and the disposition of this ledge is immediately adjacent the boundary line of the fire bed, at which point I impart to the fuel escaping over the ledge a flipped movement, thus causing the fuel particles to be spread substantially evenly over the fire bed. This flipping action is such as to not unduly

agitate the finer particles of the fuel during such spreading action.

Further objects and purposes of my invention will hereinafter become apparent from the following description which sets forth the method 5 when placed in use by the utilization of stoker mechanism disclosed in the drawings hereof.

In the drawings Fig. 1 is a side elevational view of a domestic heating furnace of the hot-air type showing my stoker mechanism associated therewith; Fig. 2 is a perspective view of the stoker mechanism when not associated with the fire door of the heating furnace; Fig. 3 is an enlarged front elevation of part of the furnace and stoker mechanism shown in Fig. 1; 10 Fig. 4 is a fragmentary cross sectional elevation taken substantially through part of the stoker mechanism when the same is in cooperative relation with the fire door of the furnace and along the line 4—4 of Fig. 3; Fig. 5 is a cross 20 sectional plan view taken through part of the stoker mechanism and substantially along the line 5—5 of Fig. 4.

My invention will be described as being carried out by the mechanism illustrated in the 25 drawings which mechanism comprises a unitary stoker mechanism which may be suspended upon an overhead trolley, whereby the fuel discharge end of the stoker mechanism may be inserted in the fire door of the furnace or withdrawn therefrom by shifting the stoker mechanism along the trolley rail which supports the same. The stoker mechanism is provided with a revolving hopper of a substantial size, whereby a sufficient mass of fuel may be charged into 30 the stoker mechanism to provide for about a twelve-hour fuel demand of the furnace during 35 the very cold seasons.

In association with the hopper mechanism and disposed immediately therebeneath is a reciprocating plunger, disposed within a substantially horizontally extending feed conduit or tube, preferably rectangular in cross section. The plunger is reciprocated by a crank shaft and pitman mechanism, which is preferably 40 driven by a speed reduction means and the oscillating reciprocation of the connecting rod or pitman serves also as a power source for causing 45 step by step revolving movement of the hopper mechanism. The horizontally extending feed 50 tube or conduit has associated therewith and at the discharge end thereof a revolving fuel flipping mechanism of definite design and having a definite relationship to an adjustable ledge, 55 associated with the inner end of the feed tube,

whereby the flipping action can be varied depending upon the physical characteristics of the particular fuel which is to be burned and the shape and area of the furnace grate. I also incorporate in the stoker mechanism a blower mechanism which is suitably associated with the ash pit of the furnace, whereby when the thermal controls function to cause operation of the stoker mechanism, a modified forced draft may be applied to the underside of the fire bed.

The foregoing outlined stoker mechanism will now be described in detail.

In Fig. 1, I show a hot-air furnace 10, provided with the usual fire door frame 11, fire pot 12 and ash pit 13. The stoker mechanism comprises a substantially large coniform hopper member 15, which is revolubly mounted upon a downwardly extending coal guiding chute in the form of a neck member 16, which, in the present design, comprises a base which supports the hopper 15 with the axis thereof oblique to a horizontal and vertical plane. The base member 16 is round at the top and rectangular shaped at the bottom, and comprises a connecting passageway between the bottom opening of the hopper 15 and a rectangularly shaped fuel feeding tube 45, attached to the bottom of the member 16. The base member 16 (see Figs. 1, 3 and 4) is provided with an annularly formed, outwardly flanged member 17 to which is attached a suspension frame comprising a downwardly extending pair of bar members 18 and 18a, arcuately shaped bar members 19 and 20, a hopper bearing bracket 21 and strap members 22. The bar members 18 and 18a, and 19 and 20 are attached at the upper ends thereof to a trolley member 23, by adjustable bolt members 24 and 25, respectively. The trolley member 23 is provided with upwardly extending trolley wheel brackets 26 and 27, bearing suitable wheels 28, which ride upon the trolley rail 30. The trolley rail may comprise a strip of standard angle iron, and the angle iron 30 is attached to rafters or floor beams 31 by any suitable means, such as straps or brackets 32 and 33 (see Figs. 1 and 2). I prefer to mount the trolley rail 30 in such manner that the bracket member 32 will suspend the inner end of the rail 30 slightly below the opposite end of the rail, whereby the rail slopes toward the furnace, thus causing the stoker mechanism to have a tendency to remain in a forward cooperating position relative to the fire box door of the furnace.

The lower end of the hopper mechanism is provided with an annular, outwardly flanged member 35, spaced a slight distance above the flange on the member 17 and which comprises both a bearing plate for the lower end of the hopper and part of the mechanism, which causes intermittently revolving movement of the hopper.

The hopper is mounted upon rollers or spools to reduce friction, and, as shown in Fig. 3, I provide bearing spools or wheels 37 and 38, which are shaped to engage the flange of the member 35, and two similar bearing spools 39 and 40. These four roller members are spaced substantially 90 degrees apart and are supported by the flange member 17. The four members are respectively mounted upon bolt studs 37a, 38a, 39a and 40a, which studs also serve to rigidly secure the lower ends of the strap members 22 and the bar members 18 and 18a, to the flange of the member 17.

The fuel feeding mechanism comprises the rectangularly formed tube 45, which is attached to and supported by the base member 16 in any suitable manner. Disposed within the outer end of the tube and slidably arranged therein is a rectangularly formed plunger member 46, which is disposed to rest immediately beneath the outer edges of the bottom of the hopper and the base member 16, whereby an unrestricted passageway is provided between the base member 16 and the top of the tube 45 throughout substantially the entire width and breadth of the bottom of the member 16. The plunger member 46 is provided with a suitable bracket 48, which carries a wrist pin 49, the wrist pin serving to engage the inner end of a fork shaped connecting rod or pitman 50. The outer end of the connecting rod 50 is operatively attached to a crank pin 51 carried by rotatable disc 52, the disc being mounted upon the end of a gear shaft 53, whereby rotation of the shaft 53 will cause a reciprocating movement of the plunger 46 within the feed tube 45, and the travel of the plunger is dependent upon the radial displacement of the crank pin 51, relative to the center of the shaft 53. The shaft 53 comprises part of a gear reduction mechanism housed within a casing 54, the casing being attached to the outer end of the feed tube 45.

Adjustment of the center of the crank pin 51 relative to the center of the shaft 53 to vary the stroke of the plunger, is afforded by the fact that the crank pin has the crank end thereof eccentrically formed.

It should be noted in Fig. 4, that the pin 51 is provided with an enlarged eccentric head 56 which coacts with the connecting rod 52. Hence, by adjusting the position of such head relative to the crank, the reciprocating movement of the plunger 46 may be varied as desired. In the present instance, the stroke of the plunger may be varied to be any distance between one inch and one and one-half inches. I provide means for preventing fuel dust from accumulating between the plunger and tube.

In Fig. 4 in cross-section is shown a tray member 58, which is slidably supported by transversely disposed plate members 59 beneath a slot 60 formed in the bottom wall of the feed tube 45 to extend substantially across the bottom thereof at a location immediately adjacent the outer edge 46a of the lower part of the plunger structure, whereby any coal dust which becomes lodged along the side and bottom walls of the plunger will be permitted to escape into the tray 58 and the slidable mounting of the tray permits removal of such dust from time to time.

I arrange at the forward fuel engaging face of the plunger 46 a fuel agitator means which rides along the bottom wall of the fuel feed tube 45, substantially the fuel conducting length thereof, and this means may be in the form of a metallic strip 80, provided with a series of transverse strips 81, shaped to comprise substantially ratchet teeth, whereby upon the forward fuel feeding movement of the plunger 46 the teeth 81 engage the lowermost particles of the fuel and thus tend to move the entire column of fuel within the conduit. This strip covers substantially one-third of the area of the bottom wall of the tube and as the plunger moves forwardly assists the plunger in shifting the column of fuel forwardly and by reason of the shape of the teeth 81 the strip has less

tendency to move the coal rearwardly upon the return stroke of the plunger. The mechanism for rotating the hopper will now be described.

The hopper 15 is revolved by means of a pawl 84, pivotally attached at its outer end to a bracket member 85, rigidly secured to the connecting rod 50 at such operative position that the pawl 84 may extend upwardly and outwardly to engage, in step by step movements, within openings 35a, equidistantly spaced and formed in the annular flange of the member 35. It will be apparent from Figs. 3 and 4 that revolving motion is imparted to the hopper during the return stroke of the plunger; thus voids momentarily created in the feed tube 45 by reason of the forward fuel feeding stroke of the plunger will be caused to be filled by reason of the agitation of the body of the fuel upon the return stroke of the plunger. A retaining pawl 87 is provided at the opposite side of the flange 35a for preventing reverse movement of the hopper.

The fuel flipper mechanism is disposed at the extreme forward or discharging end of the fuel feeding tube 45 and arranged within a housing, whereby when the entire stoker mechanism is shifted to operative position relative to the fire door, the flipper mechanism, while being disposed immediately adjacent the front boundary or wall of the fire box, will be protected by the housing, and the proportioning and design of the flipper mechanism are such that large particles of fuel cannot become lodged in any part of the mechanism which is exposed to the heat of the fire. This arrangement is also such that the stoker mechanism is readily adaptable to various sizes of fire door frames, which fire door frames vary from 9 to 15 inches in width and from 8 inches by 10 inches in height to considerably greater dimensions. The mounting of the flipper housing is such that regardless of the width of the fire door frame of the furnace, the rotary flipper member can always be adjusted to a juxtaposed position relative to the fire bed edge.

This fuel flipper mechanism comprises a revolving cylinder 70 (see Fig. 4), mounted upon a shaft 72. The shaft 72 may have a multi-step pulley 73 mounted on an extending end thereof, which pulley may be driven by a belt 74 (see Fig. 3). The belt is driven by a pulley 77, mounted upon one end of the shaft 53. The cylinder 70 is of substantially the same length as the width of the fuel feed tube 45 and the surface design thereof is of a particular functioning shape to be described in greater detail hereinafter, and is provided with an enclosing casing comprising an arcuately formed member 74, having end walls 75 to which are attached suitable bearing members 76 for rotatably supporting the shaft 72 and cylinder 70 at an operative position which is adjacent to and immediately below the inner discharge end of the feed tube 45. To support the casing comprising the member 70 and side walls 75, I provide a housing comprising a box-shaped member 90, arranged to telescope with a second box-shaped housing member 91, the latter member being secured to a door closure plate formed of any suitable material such a slab of asbestos board 92, which may be of such dimension as to comprise a closure for the largest size doors to be found on domestic furnaces of whatever type. The side walls 75 are suitably flanged, as indicated at 96 (see Fig. 5)

for rigid attachment to the housing member 90, and the width and height of the housing member 90 are such as to provide sufficient space for the enclosure of the pulley member 75, as well as the bearing members 76. The side walls 75 extend upwardly and are attached to a top member 97, which is flanged at the outer edge thereof for attachment to the box-shaped housing member 90 as shown at 98 (see Fig. 4). The member 97 is of a stepped-down formation to serve as a fuel guide or deflector to deflect downwardly any heavier particles of fuel which might be flipped upwardly at too great an angle to escape the inner edge 99 of the fire door frame, and the outer portion 97a thereof engages the top outer surface of an extension tube 100, which comprises the inner portion of the fuel feed tube 45. The top wall 90a of the box-like member 90 extends between the portion 97a and the top wall 91a of the telescoping housing member 91. The tube 100 is shaped to telescopically embrace the outer surfaces of the inner end of the tube 45, whereby the tube 100 may be of any desired length to suit the particular requirements of the installation. I provide securing means in the form of binding bolts 101 for securing the tube 100 firmly to the inner end of the tube 45. I also provide binding lugs and nuts, as indicated at 102 upon the housing member 90, and slots 104 and 105 are respectively provided, whereby the lugs may extend therethrough and clamp the housing members 90 and 91 firmly together in any desired adjusted position.

I also provide an adjustable horizontally disposed ledge member 110, which in function comprises an extension of the bottom wall of the fuel feed tube, comprising the members 45 and 100, and which serves to predetermine the falling movement of the coal particles as the same escape thereover upon the revolving flipper cylinder 70, and this member 110 may be of a suitable design to be disposed immediately between the uppermost path of rotating movement of the member 70 and the bottom wall of the fuel feeding tube, and, as shown in Fig. 4, the member 110 is provided with downwardly extending slotted flanges 110a, and a clamping bolt 111 of any convenient design may extend through the slots in the flanges, whereby the member 110 can be secured in any desired adjusted position. Graduations, as indicated at 112 may be provided on one of the side walls 75 to indicate to the adjustor the degree of adjustment of the ledge member 110, relative to a vertical plane extending through the axis of the flipper frame 70.

In order to eliminate the necessity for the use of damper motor controls, I provide a blower mechanism, which may be operated only when the stoker mechanism is functioning to feed fuel to the fire bed. This blower mechanism may comprise the conventional type of blower casing 120 and an impeller 121, the casing 120 being secured to the casing of the power motor 123, and the impeller 121 being suitably secured to one end of the motor shaft 124. Depending from the blower casing 120 is a flexible tube 125, which may extend downwardly to the ash door 126 of the furnace structure and extend through a suitable opening 127, formed in the ash pit door. The blower casing 120 is provided with an air inlet opening indicated at 180 (see Fig. 4) and the volume of air passing through inlet 180 is determined by an adjust-

- able disc-shaped member 181 which has a screw thread mounting upon a threaded stud 182, carried by the blower casing. Adjustment of the volume of air is obtained by moving the disc 181 axially toward or away from the openings 180 in the casing 120. The volume of air required is determined by the size of the fire bed, the burning characteristics of the fuel to be used and the heat delivery demands made upon the furnace by the thermostatic controls. Hence, adjustment of the disc 181 relative to the air inlet opening of the blower casing will be determined by operating trials of the stoker mechanism at the time of installing the same.
15. The motor 123 may be suitably mounted in an inverted position upon a bracket member 128, adjustably secured by bolts 129 to a depending bracket member 130, secured to the bottom wall of the fuel feed tube 45 at a convenient position 20 to permit practical driving connections between the pulley 132 mounted upon one end of the motor shaft 124 and pulley 133, mounted upon the shaft of the gear reduction mechanism. A suitable belt 134 serves to drivingly connect the 25 pulleys 132 and 133. It will thus be apparent from Fig. 3 that various speed selections may be made by reason of the provision of step pulleys 13, 11, 132 and 133, respectively mounted upon the flipper cylinder shaft, on the gear reduction 30 shaft, and motor shaft.
- It should be noted that the relationship of the rotatable flipper member 70 relative to the inner discharge end of the fuel feed tube and to the rim of the fire pit is such that the desired flipping action on the fuel particles can be obtained 35 without causing undue agitation of the fuel particles. The plunger makes from 1 to 3 strokes per minute and the fuel displacement along the tube is from 1 inch to 1½ inches per plunger 40 stroke. The size of the rotatable member 70 is such that it can be disposed immediately beneath and adjacent to the discharge end of the tube and also can be disposed in such position that the flipping action thereof will not cause 45 the coal particles to be thrown too violently. The dimensions of the tube in cross-section are approximately 4 inches high and 6 inches wide and the flipper member extends the full width of the tube. The dimensions of the flipper member thus will be apparent. The speed of the flipper member can be varied from 300 R. P. M. to about 900 R. P. M., and the correct speed 50 will be dependent upon the size of the fire bed and the physical characteristics of the fuel to be fed thereto.
55. The surface of the flipping member 70, as shown in the drawings, comprises veins or blades 70a, preferably integrally formed about the perimeter of the flipper member to taper toward the center thereof, thus imparting to the fuel 60 particles not only an outward throw from the discharge end of the tube, but also an angular throw relative to the tube center line. I also form the surface 70b of the rotatable member, as shown in Fig. 4, in such manner that at such 65 times as the stoker mechanism is at rest any coal particles, which may drop from the inner end of the tube cannot become lodged within the semi-circular housing member 74 nor at the 70 point 74a comprising the forward arcuate terminus of the member 74. I also provide a chute 74b on the housing 74, extending downwardly from the forward terminus 74a thereof to guide any light particles of fuel which might 75 fall when the stoker is at rest, so that at no time

are there any fuel particles exposed to the heat of the fire bed, which particles could in any way become ignited and thus cause the ignition of the fuel which is at rest within the feed tube.

My prior experimenting with stokers of the overfeed type has disclosed that a feed tube carrying fuel cannot be extended into the fire box without the attendant difficulties. Under such a condition, the fuel when in the tube has a tendency to coke, thus liberating tar and other sticky components of the average fuel. Likewise, there is always present a fire hazard under such circumstances. It will be apparent from the design disclosed in the drawings that my method of overfeed stoking of a furnace can be successfully performed on different types of domestic heating furnaces while the difficulties and dangers above mentioned are avoided.

Likewise, the design discloses a practical form from a commercial viewpoint, in that regardless of variations in the width of the fire door frame 11, the inner end of the tube and the flipper mechanism can always be adjusted to the proper relationship relative to the rim of the fire pit by reason of the telescoping construction of the flipper housing and by reason of the fact that I provide the fuel feeding tube 45 with the extension tube 100, thus making the installation of the stoker mechanism readily adaptable to various furnace structures.

My method has been applied to anthracite fuel of the so-called pea-size, as well as to anthracite culm and bituminous slack coals of both high and low grade, and by reason of the manner in which I control the application of these fuels to the top of the fire bed, I have been able to meet widely varying conditions.

It will be apparent to those skilled in the art that the mechanism as arranged in the designs may be constructed primarily from sheet metal and preferably ingot iron sheets, which will resist corrosive action, and the entire arrangement will be readily responsive to the operative regulation of any of the standard thermostatic control devices now on the market.

I am aware that flipper mechanisms for throwing coal onto a fire bed have been proposed heretofore. Such mechanisms have usually been associated with some form of blower means functioning through the fire door. I have devised a flipper mechanism which avoids the use of a blower and I thus avoid the escaping of partially burnt coal dust up the chimney. Protracted testing of my stoker demonstrates the importance of agitating the mass of fuel while removing measured quantities thereof and the ledge principle of fuel escape makes the controlling of the flipping action practical, whereby the powdered portion of the fuel will not be unduly agitated to the extent that the same would be caused to escape up the flue without being burned. The apparatus has been quite successful in stoking a variety of fuels, while maintaining a proper fire bed that will produce very low ash and low fuel losses.

I claim:

1. The method of feeding fuel to a fire bed, comprising intermittently revolving a mass of fuel on an axis disposed obliquely to both vertical and horizontal planes while permitting part of the mass to gradually escape at the bottom thereof, shifting that part of the fuel which has escaped from the revolving mass in a substantially horizontal direction toward the fire bed during the period when the revolving mass is at

rest and finally imparting to the fuel particles a flipped movement to cause the fuel particles to be spread over the fire bed.

- 5 2. The method of feeding fuel to a fire bed, comprising intermittently revolving a mass of fuel about an axis while permitting part of the mass of fuel to gradually escape at the bottom of the mass, intermittently shifting that part of the fuel which has escaped from the revolving mass in a substantially horizontal direction toward the fire bed while the revolving mass is stationary, and finally imparting to the fuel particles a flipped movement to cause the fuel particles to be spread over the fire bed.
- 10 15. 3. The method of feeding fuel to a fire bed, comprising revolving a mass of fuel on an axis disposed obliquely to both vertical and horizontal planes while permitting part of the mass to gradually escape at the bottom thereof, shifting that part of the fuel which has escaped from the revolving mass in a substantially horizontal direction toward the fire bed to effect a falling movement of the fuel particles in a region adjacent the fire bed edge and finally imparting to the fuel particles as they are thus falling a flipped movement to cause the fuel particles to be spread over the fire bed.
- 20 25. 4. The method of feeding fuel to a fire bed, comprising revolving an entire mass of fuel on an axis disposed obliquely to both vertical and horizontal planes, shifting the lowermost part of the mass of fuel in a substantially straight line direction toward the fire bed to cause part of the fuel as it is thus shifted to escape with a falling movement adjacent to and toward the boundary line of the fire bed and imparting to the fuel particles as they are escaping a flipping action, whereby the escaping fuel is caused to be spread over the fire bed.

in a substantially horizontal direction toward the fire bed while permitting part of the shifted fuel as it is being shifted to drop vertically adjacent the boundary line of the fire bed and imparting to the fuel particles as they are thus falling a flipped movement, whereby the fuel is caused to be spread over the fire bed.

5 10 15. 5. The method of feeding fuel to a fire bed, comprising revolving an entire mass of fuel on an axis disposed obliquely to both vertical and horizontal planes, shifting the lowermost part of the mass of fuel in a substantially straight line horizontal direction toward the fire bed, permitting part of the fuel as it is thus shifted to escape by a falling movement adjacent to and toward the boundary line of the fire bed and imparting to the fuel particles as they are escaping a flipped movement, whereby the fuel is caused to be spread over the fire bed.

20 25. 6. The method of feeding fuel to a fire bed, comprising revolving a mass of fuel on an axis disposed obliquely to both vertical and horizontal planes, shifting the lowermost part of the mass of fuel in a substantially straight line direction toward the fire bed to cause part of the fuel as it is thus shifted to escape with a falling movement adjacent to and toward the boundary line of the fire bed and imparting to the fuel particles as they are escaping a flipping action, whereby the escaping fuel is caused to be spread over the fire bed.

HERMAN L. KRAEFT.
